UNITED STATES PATENT OFFICE.

FREDERICK H. WESTON, OF SCHENECTADY, NEW YORK, ASSIGNOR TO GENERAL ELECTRIC COMPANY, A CORPORATION OF NEW YORK

CURRENT CONNECTION FOR ELECTRIC LAMPS.

1,209,526.

Specification of Letters Patent. Patented Dec. 19, 1916.

Application filed December 26, 1914. Serial No. 879,051.

To all whom it may concern:

Be it known that I, FREDERICK H. WESTON, a citizen of the United States, residing at Schenectady, county of Schenectady, State of New York, have invented certain new and useful Improvements in Current Connections for Electric Lamps, of which the following is a specification.

My invention relates to current connections such as are used for electric lamps and the like, and it includes both bases or plugs and corresponding sockets or receptacles that are especially suitable for the mounting and electrical connection of such lamps, though also applicable and adaptable to other uses.

The invention is more particularly concerned with the transmission of such relatively heavy currents as are required, by high candle power tungsten filament incandescent lamps containing nitrogen or other gas or vapor and operating at very high efficiency. It is important that when such a lamp is inserted in a socket or receptacle each of the connections necessary to complete its circuit should be made with good contact over ample area, in order that the parts shall not be liable to injurious or dangerous overheating, and also for other reasons. How this and other requirements can be met and various advantages obtained through my invention will appear from the following discussion and from the detailed description of particular embodiments hereinafter, while its scope will be indicated in my claims.

In accordance with my invention, I secure good contact and current carrying capacity by providing the base or plug device with terminals having coacting screw threaded contact surfaces and providing the socket or receptacle device with terminals having corresponding screw threaded contact surfaces, so that each of the connections necessary to complete the circuit is a screw thread connection. Meshing and engagement of the screw threads of both the base terminals with those of the socket or receptacle terminals when the lamp is screwed into the socket can be insured by making the terminals of one of these connection devices movable (in some degree, at least) relatively to one another when engaging those of the corresponding device, so as to compensate for any initial lack of corre-

spondence between screw threads. For this purpose, one of the socket terminals may be axially movable in either direction, or may be capable of rotary movement. The movable or "floating" socket terminal may advantageously be arranged to resist movement or displacement by the corresponding base terminal, as by making it resiliently yielding, although the relative mobility of the coacting terminals can be made to assure good contact and pressure between the contact surfaces in other ways besides this.

The utility of the relatively movable terminal arrangement is not confined to a connection device all of whose coacting contact surfaces are screw threaded, but extends, also, to a connection device having screw threaded terminals and plain terminal means all coacting with one another.

In the accompanying drawing, Figure 1 is a mid-sectional view illustrating a very simple lamp base and socket construction embodying my invention. Fig. 2 is a similar view illustrating a different construction. Fig. 3 is a fragmentary detail view of a part of the structure shown in Fig. 2. Fig. 4 is a fragmentary view, partly in section, showing a lamp with a type of base different from that shown in Fig. 1. Fig. 5 is a mid-sectional view of a socket or receptacle adapted to take the base shown in Fig. 4. Fig. 6 is a perspective view of a part of the receptacle shown in Fig. 5. Fig. 7 is a perspective exterior view of the receptacle shown in Fig. 5. Fig. 8 is a bottom view of the receptacle shown in Figs. 5 and 7, and substantially represents the bottom of that shown in Fig. 1 also. Fig. 9 is a mid-sectional view illustrating a construction similar to that of Figs. 5, 7 and 8, but more especially adapted for use in exposed situations out of doors. Fig. 10 is a plan view of the lower part of the socket shown in Fig. 9. Fig. 11 is a view of the upper part of the socket shown in Fig. 9 as seen from beneath.

As shown in Fig. 1, the terminals of the lamp base 1 consist of two electrically separate screw threaded shells 2 and 3 of different diameters or sizes, arranged coaxially one within the other and mechanically united by a body of insulating material 4. For the sake of a large cavity for the end of a high power lamp, the base 1 is provided with an ordinary enlarged and insulated skirt 5. The current leads 6 and 7 of the lamp are

soldered to the terminals 2 and 3 in very much the usual way.

The socket or receptacle 11 which receives the base 1 comprises electrically separate screw shell terminals 12 and 13 also arranged coaxially one within the other, the former being of such diameter that the large base terminal 2 will screw into it easily but snugly, and the latter being similarly adapted to screw into the small base terminal 3. The terminals 12 and 13 are mounted on an insulating body structure 14 which forms a casing about them, the large terminal 12 being fixedly secured by screws 15, while the smaller terminal 13 is spring mounted so as to be resiliently yielding in an axial direction. The movable terminal 13 may be in the form of a cup or cap-like screw shell, and as shown it has an angular shank or stud 17 extending downward from its bottom through an angular hole in the base portion of the body structure 14 and into a circular recess at the lower side of said portion. A helical compression spring 19 around the shank 17 a disk-like head 20 secured thereto by a screw and the bottom of the aforesaid recess urges the terminal 13 inward away from the mouth of the terminal 12. The inward movement of the terminal 13 is limited by an insulating washer in the bottom of the large terminal 12 (or, in its absence, by the body structure 14 itself), while outward movement of said terminal is limited by abutment of the head 20 around the recess containing the spring 19. The current connection to the terminal 12 is through two of the screws 15, while that to the terminal 13 is through the shank 17 and a flexible laminated lead clamped to it by the disk or washer 20. As these connections are similar to those shown in Figs. 5 and 8 and hereinafter described in detail, no further description of them is necessary.

It will be seen that the movable or "floating" terminal 13 with its associated parts is restrained or prevented from turning relatively to the terminal 12 and its associated body structure 14 by the engagement of the shank 17 with the said body structure, and that axial movement or displacement of said terminal 13 from the position shown (which is its normal one) is yieldingly resisted by the spring means 19. When the base 1 is turned clockwise to screw it into the socket 11, it comes into concurrent threaded engagement with both of the socket terminals 12 and 13; but, as shown, the threads of the base terminal 3 will mesh and engage with those of the loose or floating socket terminal 13 before the base terminal 2 encounters the socket terminal 12. When such encounter does take place,—which is the position of the parts shown in Fig. 1,—the threads of the base terminal 2 will immediately mesh and engage with those of the fixed socket

terminal 12 if the angular arrangement of the various terminals permits; otherwise the movable socket terminal 13 will be drawn upward by further turning of the base 1 until such meshing and engagement can take place. This action will obviate any difficulty that might otherwise arise from bad workmanship or careless assembling; and if the socket terminals 12 and 13 are so arranged that the latter will necessarily be displaced against a fairly stiff, strong spring 19 of suitable scale, it will also insure good contact and pressure on all the screw threaded contact surfaces.

If the screw threads of all the terminals are of the same pitch, the screwing of the base 1 into the socket 11 will present no peculiarity after both the base terminals have come into mesh with the socket terminals as above described, while if the threads of the terminals 3 and 13 are of greater pitch than those of the terminals 2 and 12, the further screwing in of the base 1 will result in further upward movement of the floating terminals 13 against the spring 19. Such differential threading of the terminals therefore facilitates securing good contact pressure between them; and it also allows this to be done without the spring 19, in a way that will appear hereinafter in connection with Figs. 4 and 5.

The socket or receptacle 21 shown in Fig. 2 is adapted to take the base 1 shown in Fig. 1, but it differs from the socket 11 of Fig. 1 in that the spring mounted loose or floating terminal 23 is movable angularly instead of axially. Accordingly, the shank 27 and its hole in the bottom portion of the body structure 24 are made cylindrical so as to permit the terminal 23 to turn, and the turning is yieldingly resisted or restrained by a springy wire 29 bent to an appropriate form and serving as a flexible current connection for the terminal 23. The turning of the terminal 23 may be limited to any desired angle by one or more projections 30 from the shank 27 (see Figs. 2 and 3) which lie in one or more recesses 30a in the base portion of the body structure 24. This arrangement gives an action similar to that of Fig. 1, and offers similar possibilities as regards defects and errors in the factory, contact pressure, differential threading, and dispensing with the spring 29.

Referring, now, to Fig. 4, it will at once be seen that the base 31 here shown differs from the base 1 of Fig. 1 in that its electrically separate coaxial screw shell terminals 32 and 33 are arranged endwise and that the screw threaded contact surfaces of both are external. Preferably the pitch of the screw threads of the large terminal 32 is greater than that of the threads of the small terminal 33. The terminal 32 may be of the same size as the screw shell of the

base commercially known as the "Mogul", and the terminal 33 of the size of the screw shell of the ordinary medium base, and the insulating material 34 may unite 5 them mechanically to one another and to the enlarged skirt 35 in the manner illustrated in U. S. Patent No. 775,689 to Swan, granted November 22, 1904. As shown, the terminal shell 33 is not made as a closed cap 10 like the terminal 3 of Fig. 1, but with an open lower end from which the insulation 34 projects enough to insure against the production of a short circuit if an ignorant person should screw the lamp into an 15 ordinary medium screw socket.

Referring to Fig. 5 it will be seen that the socket or receptacle device 41 for the base or plug device 31 has screw shell terminals 42 and 43 which are arranged one within 20 the other with their coating internal differentially screw threaded contact surfaces coaxial and are movable relatively to one another when engaging the corresponding base terminals 32 and 33. The terminals 42 and 43 are mounted on a body structure 44 of porcelain, bisque, or other insulating material which forms a casing about them, the large terminal 42 being fixedly secured by screws 45, while the small terminal 43 is 25 spring mounted so as to be resiliently yielding in an axial direction. As shown, the terminal shell 43 is in the form of a cup with an angular hole in its bottom, and it is externally insulated by an inclosing cup or 30 caplike shell 46 of fiber, porcelain, bisque, or other insulating material. For mounting the movable or "floating" terminal 43 with its insulating covering 46 is employed a stud 47 (see Fig. 6) formed of sheet metal 35 suitably punched, bent, and riveted, etc. The head of this stud 47 lies at the bottom of the terminal 43 and may be soldered or otherwise fastened thereto, and its angular 40 yoke-like shank 48 extends through angular holes in the parts 43 and 46 and through a similar hole at the bottom of a circular recess in the base portion of the body structure 44, and thus the terminal 43 with its associated parts is restrained or prevented 45 from turning. A heavy helical compression spring 49 in this recess around the shank 48 urges the terminal 43 with its associated parts outward toward the mouth of the terminal 42, and yieldingly resists axial 50 movement or displacement of said terminal 43 from the position shown, which is its normal one. The outward movement of the terminal 43 is limited by a piece 50 secured by a screw to the shank 48 and projecting 55 beyond the edges of the hole in the body structure 44 through which said shank extends, while its inward movement is limited by the body structure 44 itself.

Referring to Figs. 5, 7 and 8, it will be 60 seen that the insulating body structure 44

is provided with a pair of lugs or feet 51 pierced to receive screws for securing the socket in position, and also with lugs 52 which carry binding posts 53, 54 for the connection of the current supply wires. 70 From the binding post 53 electrical connection to the terminal 42 is through two screws 55, a metal piece 56 in a recess at the bottom of the body structure 44, and two of the screws 45; from the binding post 54 it is 75 through two screws 57, a metal piece 58 with which they engage, and a flexible laminated lead 59 composed of a number of these copper strips soldered to said piece 58 and clamped to the shank 48 by the piece 50. 80

When the base 31 is inserted in the socket 41 and turned clockwise, it comes into concurrent threaded engagement with both of the socket terminals 42 and 43. Preferably the socket parts are so proportioned and arranged that meshing and engagement occur between the terminals 32 and 42 before the terminal 33 encounters the terminal 43; for with this action any failure of the terminals 33 and 43 to mesh when they first 90 come in contact (owing to defective workmanship or error in assembling the parts) will not cause jamming, but merely result in the loose or floating terminal 43 being forced inward rather rapidly by further 95 turning of the base 1 until the terminal 33 does mesh and engage with it properly. Once the terminals 32 and 42 and 33 and 43 are in threaded engagement, further turning of the base 31 will force the loose or 100 floating terminal 43 slowly inward at a rate depending on how much less its pitch is than that of the terminal 42, and the resulting progressive compression of the spring 49 will cause a progressively increasing binding 105 effect upon the engaging screw threaded terminals. The final or limiting condition will preferably be at the inner limit of movement of the terminal 43.

It will be seen that when the base 31 is 110 screwed well into the socket 41 the compression of the spring means 49 (if it be a fairly stiff, strong spring of suitable scale) resulting from the differential threading of the terminals will insure good contact pressure over a good area. The spring 49 can, however, be dispensed with or made too weak to produce such pressure and good result obtained if the base 31 is simply screwed into the socket 41 until the floating 120 socket terminal 43 is firmly jammed or wedged at the inner limit of its movement, the parts being, of course, so designed that such jamming will occur before the base terminal 33 bottoms in the 125 socket terminal 43. Again, the pitches of all the terminal threads may be made the same and the socket terminals 42 and 43 purposely so arranged relatively to one another and to the base terminals that when 130

the base is screwed into the socket the base terminal 33 will not mesh and engage with the movable socket terminal 43 when it first encounters it, but only after it has forced it inward a certain distance against the resistance of a fairly stiff, strong spring 49.

Referring, now, to the socket 61 shown in Figs. 9, 10 and 11, it will be seen that the body structure 64 and the electrical parts are so similar to the corresponding parts shown in Figs. 4, 5, 6, 7, and 8, that no particular description of them is necessary. As, however, this socket 61 is intended to be suitable for situations where it is directly exposed to the weather, the feet shown in Figs. 5, 7, and 8 are dispensed with and the upper insulating piece or cap 71 is provided. On the upper side of the cap 71 an internally threaded metal supporting collar 72 is secured by screws 73—a gasket 74 being interposed to make the joint watertight,—while at the lower side of said cap metal terminal and securing pieces 75 are secured by means of screws 76. The inner ends of the pieces 75 are in a recess in the lower side of the cap 71 and are provided with binding screws 77 for the attachment of current leads, while their outer ends extend beyond the periphery of the body 64 and are provided with clamping screws 78. A terminal and securing piece 80 with notches 81 is secured in a depression in the upper end of the body 64 by two of the screws 65 that hold the large socket terminal 62 in place, and a similar piece 82 is secured diametrically opposite by nuts 83 on studs or bolts insulatively secured in said body 64.

It will be seen that by putting the body 64 in place in the cap 71 (or vice versa), turning the body (or the cap) a little in a clockwise direction, and tightening up the screws 78 the cap and body will be securely fastened together and the current leads will be electrically connected to the socket terminals. It will be understood, of course, that the large socket terminal 62 is electrically connected to the piece 80 through the screws 65, and that the movable socket terminal 63 is connected to the other piece 82 by a T-shaped laminated flexible conductor 69 one of whose ends is clamped to the shank of the movable terminal by the part 70 and whose other ends are clamped beneath the nuts 83. It will be seen that the outer edge of the cap 71 extends down around the upper end of the body 64 in a sort of hood with an annular ventilating space between, and that the socket is ventilated and cooled by means of two passages 84, 84, that extend up around its terminal 62 as grooves in the inner surface of the hollow portion of the body structure 64 and are prolonged into the space beneath

the hood as holes 85, 85 through the base 65 portion of said body structure.

While I have, in accordance with the requirements of the patent statutes, shown and described the best form of embodiment of the invention known to me, I do not desire to restrict myself thereto; moreover, I hereby wish to disclaim inventorship of the broad idea of coacting threaded contact surfaces of different diameters and the differential threading of terminals, the same being respectively the inventions of Howard R. Sargent and John A. Orange.

What I claim as new and desire to secure by Letters Patent of the United States, is:—

1. A connection comprising a socket or receptacle device having terminals with coacting screw threaded contact surfaces and a base or plug device for said socket having terminals with corresponding screw threaded contact surfaces, the terminals of one of said devices being movable relatively to one another.

2. A connection device comprising terminals with coacting screw threaded contact surfaces, said terminals being movable relatively to one another when coming into engagement with those of a corresponding connection device.

3. A connection device comprising terminals with coacting coaxial screw threaded contact surfaces, one of said terminals being axially movable by a corresponding connection device.

4. A socket or receptacle comprising terminals with coacting coaxial screw threaded contact surfaces of different diameters, said terminals being axially movable relatively to one another when coming into engagement with those of a corresponding base.

5. A socket or receptacle comprising terminals with coacting screw threaded contact surfaces, said terminals being resiliently yielding relatively to one another when coming into engagement with those of a corresponding base.

6. A socket or receptacle comprising terminals with coacting coaxial screw threaded contact surfaces; one of said terminals being fixed and the other spring mounted so that it may yield axially.

7. A socket or receptacle comprising a fixed large terminal part having internal screw threaded contact surfaces, a smaller terminal part within the large terminal part which also has screw threaded contact surfaces and is so engaged with the large terminal part as to be movable axially to a limited extent but restrained from turning relatively thereto, and spring means urging said smaller terminal part toward one limit of its movement.

8. A socket or receptacle comprising a

body structure and a large screw shell terminal fixedly secured thereto, a smaller screw shell terminal within said larger one having a shank so engaged with said structure as to prevent said smaller terminal from turning while allowing it a limited axial movement, and a helical compression spring about said shank whereby said

smaller terminal is urged toward one limit of its movement.

10

In witness whereof, I have hereunto set my hand this 24th day of December, 1914.

FREDERICK H. WESTON.
